(57) **CLAIM**

The ornamental design for a portable light, as shown and described.

DESCRIPTION

FIG. 1 is a front, right and top perspective view of a portable light showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an exploded view of the portable light.

The broken lines in the figures illustrate portions of the portable light that form no part of the claimed design.
